UNITED STATES PATENT OFFICE.

HENRY W. JACOBS AND HOWARD H. LANNING, OF TOPEKA, KANSAS.

ACETYLENE-GENERATING APPARATUS.

1,152,512.

Specification of Letters Patent.

Patented Sept. 7, 1915.

Application filed March 23, 1914. Serial No. 826,661.

To all whom it may concern:

Be it known that we, HENRY W. JACOBS and HOWARD H. LANNING, citizens of the United States, residing at Topeka, in the county of Shawnee and State of Kansas, have invented certain new and useful Improvements in Acetylene-Generating Apparatus, of which the following is a description, reference being had to the accompanying drawings, which form a part of our specification.

Our invention relates more especially to means intended for use in connection with the generating cells of an acetylene generating apparatus and the like; being especially intended to securely lock or hold the covers of the generating cells in place and simultaneously affect the valve-mechanism whereby the water supply is controlled in its passage to the generating cells; the object being to provide a construction whereby the fluid or water cannot flow into the generating cells while the cover or covers are open or unlocked, as will be more fully understood from the following detailed description thereof.

In the drawings:—Figure 1 is a plan view of our improvement shown applied to a generating cell of an acetylene generating apparatus, the water-supply and gas take-off conduits being shown broken away. Fig. 2 is a side elevation thereof, showing the cover and means in closed or locking position. Fig. 3 is a side elevation thereof showing the cover and means in unlocking position. Fig. 4 is a plan view of a modified form of our construction. Fig. 5 is a side elevation thereof showing the cover holding portion in closed or locking position, while the valve-control portion is in open position. Fig. 6 is a sectional view showing the means in unlocking position.

In the particular exemplification of our invention as illustrated in the drawings, we show it applied to a single cell of an acetylene generator and more particularly to the type wherein acetylene is generated by feeding water to the calcium carbide.

The invention is especially adapted for use in connection with the covers of the generating cells; one of its functions being to securely hold the cover in closed position; the construction and arrangement being such that the position of the means will affect and determine the position of the valve or

valves whereby the water supply for the generating cells is controlled.

In the drawings, the invention is shown applied to a generating cell 10, which is preferably arranged within a cooling chamber 11, adapted to be supplied with cooling water surrounding the cell 10. The cell 10 may be of any desired form, being preferably shown in the nature of a cylindrical casing permanently closed at its one end, 65 where it is shown provided with a suitable bracket 12, which rests upon a bracket 13 secured to the rear wall of the cooling chamber 11, whereby it receives proper support, while the forward end of the cell is made 70 to extend through the front wall of the cooling chamber. The forward extended end of the cell is provided with a suitable cover or lid 14 which is shown to swing in a vertical direction. The cover or lid 14 is preferably provided with an upwardly extending lug 15 curved rearwardly as shown so as to be brought into juxtaposition with the lug 16 which is preferably formed integral with the extended end of the cell or casing, as 80 very clearly shown in Figs. 1 and 2. The lug 16 is preferably provided with a horizontally disposed slot as shown at 17, in Figs. 2 and 3, through which the hinge-forming pin 18 extends, thus permitting 85 slight horizontal play between the lugs, or rather of the pin 18 in the slot 17, and thereby enable the cover 14 to uniformly bear against its seat on the end of the cell; in other words, the construction is such that 90 the lower or unhinged part of the cover may be placed under the same pressure as the upper or hinged part thereof and thus permit a gas-tight connection between the cover and the end of the cell being effected.

Pivots secured to the outer end of the cell 10, and at points preferably diametrically opposite each other, is a yoke 19 which is free to swing upwardly as indicated in Fig. 3; being held against downward movement, that is, below the horizontal plane of its pivots, by suitable lugs or webs 20 which may be formed integral with or secured to the cover 14; the webs or lugs 20 preventing the movement of the yoke 19 below what 105 may be termed "dead center" position.

The yoke 19 and the cover 14 are connected at their centers by suitable struts which consist, in the construction shown, of the internally threaded socket member 21 piv- 110

totally secured at the point 22 between the inwardly presented lugs 23 formed integral with the yoke 19; the internally threaded socket member 24 pivotally secured to the cover 14; and the oppositely threaded screw 25 which practically constitutes a turn-buckle connection.

It is evident from the construction shown and described, that rotation of screw 25 in one direction will place the cover 14 under pressure, so that when the yoke 19 is swung downwardly into the horizontal position shown in Figs. 1 and 2, the cover 14 will be held against the end of the cell 10 with the necessary pressure thereon to maintain a gas-tight connection. It will be further evident from the construction shown and described that after screw 25 has been adjusted, the necessary pressure will instantly be obtained as soon as the yoke has been moved into the horizontal or locking position.

One side of the yoke 19 is provided with a lug 26, preferably at a point in proximity to the pivotal point of the yoke, as very clearly shown in Figs. 2 and 3, which is adapted to engage with the link 27 pivotally secured at the point 28 to the side of the cell. The link is preferably provided with a curvature 30 at a point in proximity to its pivotal point 28, to correspond with the arc described by lug or projection 26 when the yoke is oscillated, in order to permit the complete upward movement of yoke 19 into the unlock-35 position shown in Fig. 3. The link 27 is pivotally secured at its upper end to link 29 which latter is pivotally secured to rod 30; while rod 30 is in turn pivotally secured to the short arms or levers 31 and 32 secured 40 to the valves 33 and 34, respectively. The valves 33 and 34 are arranged in conduits 35 and 36 respectively, whereby water is conveyed to the forward and rearward ends of the generating cell 10 when the valves are 45 in open position. The unconnected end of rod 30 is shown bent upwardly at 30° in order to provide a suitable grasp whereby the rod may be reciprocated by hand after the cover and the holding mechanism have been 50 moved to locking or closed position, thus enabling the valves 33 and 34 to be moved to open position and permit the water or fluid to pass through conduits 35 and 36 respectively. The connection 55 between the valves and the various rods or links is such that when the valves are in open position, the links or rods will be presented forwardly into the position shown in Fig. 2, thus bringing the link or member 60 27 into contact with or in close proximity to the projection or lug 26 on the yoke 19, so that the unlocking of the cover of the cell will simultaneously operate the water controlling valve-mechanism and thus prevent 65 the undesirable flow of fluid or water

through conduits 35 and 36 at a time when access to the cell or chamber 10 is desired. The curvature provided in the link 27 permits the link to be pivoted into close proximity to the point of the yoke, and at the 70 same time permits the lug or projection 26 to swing through the arc of a circle during the lifting movement of yoke 19 and the cover 14 into the position illustrated in Fig. 3.

In Figs. 4 to 6, inclusive, we show a modified form of the invention, wherein the cell is provided with the water supply conduits 35^a and 36^a fed by means of a single conduit 37 and the branch or line 37^a. In this construction the conduit 37 at a point in 80 advance of conduit or supply pipe 35^a is provided with a suitable valve 38, which may either be spring-controlled or gravity operated and provided with a depending stem or rod 39 adapted to extend down 85 along the side of the forward end of the cell or chamber 10, as very clearly illustrated in Fig. 5; the length of the stem being substantially equal to the distance between the valve 38 and the horizontal plane in which 90 the pivotal point of yoke 19^a is located.

In the construction illustrated in Figs. 4 to 6 inclusive, the yoke 19^a and the cover 14^a are arranged to swing in opposite directions, and, therefore, independent of one another, 95 so far as movement is concerned. In this construction, the cover 14^a is provided with a similar lug 15^a arranged to extend downwardly instead of upwardly and curved so as to be brought into juxtaposition with the lug 16^a formed on the under side of the forward end of the cell or chamber 10; the lug 16^a, like lug 16, being provided with a horizontally disposed slot 17^a adapted to receive the hinge-pin of the cover and at the same time permit slight horizontal movement at the lower side of the cover in order that equal pressure may be exerted on all points of the cover through the application of the turn-buckle mechanism composed of the threaded socket member 24^a, which is pivotally secured in a suitable manner to the yoke 19^a and receives the oppositely threaded screw 25^a on the opposite end of which is secured the internally threaded socket member 21^a, the free end whereof may be provided with the laterally disposed projections 21^b. The laterally disposed projections 21^b, more clearly shown in Fig. 4, 105 are adapted to extend into the socket 40 provided on the cover 14^a, the socket 40 being preferably shown provided by means of the lug or projection centrally disposed on the cover as very clearly shown in Fig. 6. The yoke 19^a is provided with a projection 41 beyond the pivotal point of the yoke as clearly shown in Fig. 5; the projection 41 being arranged to extend into the vertical plane of the depending stem 39 of valve 38, so as to come into engagement with the 110 120 125 130

lower end of stem 39 when the yoke 19^a is 5
swung downwardly into the horizontally
locked position indicated in Fig. 5. Like
the construction shown in the first figures
of the drawings, the cover 14^a may be pro-
vided with the lugs or lobes 20^a at a point
beneath the horizontal plane of the pivotal
point of the yoke, so as to prevent move-
ment of the yoke below the horizontal plane
10 of the center of the cover, namely beyond
what may be termed "dead center" position.

It is evident from the construction just
described, as illustrated in Figs. 4 to 6 in-
clusive, that when it is desired to have ac-
cess to the generating cell, it will be neces-
sary to lift yoke 19^a upwardly into the posi-
tion shown in Fig. 6, which will move the
pressure applying turn-buckle mechanism
out of contact with the cover 14^a and allow
20 the latter to be swung downwardly as indi-
cated in Fig. 6. The upward movement of
yoke 19^a will swing its rearward extension
or lug 41 through the arc of a circle and out
of contact with the lower end of stem 39,
25 thus permitting gravity, or other forces, to
move the valve 38 to closed position, there-
by shutting off the flow of fluid or water
from conduit 37 into conduits 35^a and 36^a
30 by means of the connection or branch 37^a.
As soon as it is desired to start generation
in the cell, namely after the cell has been re-
charged with proper calcium carbide, the
cover is swung to closed position and the
yoke dropped into the horizontal position
35 shown in Fig. 5, simultaneously swinging
the free end of the turn-buckle connection
into the socket 40 of the cover, whereby the
proper or determined pressure will be ap-
plied to the cover. The movement of the
40 yoke into the horizontal position brings the
extension or lug 41 upwardly into contact
with the lower end of stem 39 and lifts the
valve against the exerting forces, thus al-
lowing the fluid or water to pass from con-
duit 37 into the respective conduits leading
45 to the cell.

We have shown and described our inven-
tion applied to generating cells receiving
their water supplies at opposite ends; but
50 it will be readily understood that any num-
ber of supply pipes and valves may be pro-
vided and the valve mechanism controlled
substantially as herein shown and described;
the invention being more particularly in-
55 tended to prevent the improper flow of wa-
ter to the generating cells of an acetylene
generating apparatus. It will be under-
stood, however, that the invention may be
60 applied to devices of a different character
wherein it is desirable to have the position
of the cover determine the position of a
valve or valves controlling the passage of a
fluid into the receptacle.

We have shown and described what we
65 believe to be the simplest and best forms of

the invention, but it will be understood that
modifications might be made without, how-
ever, departing from the spirit of the in-
vention, and we do not wish therefore to be
understood as limiting ourselves to the ex- 70
act construction shown and described.

What we claim is:—

1. In an apparatus of the class described,
having a generating cell provided with a
cover and one or more water conduits lead- 75
ing to the cell, said conduits being provided
with shut-off valves, a member pivotally
secured to the cell, means pivotally secured
to said member and arranged to have oper-
ative relation with the cover, said means 80
being adjustable lengthwise thereof so that
movement of the member and means into
parallel position will exert predetermined
pressure on the cover and maintain the lat-
ter in closed position, and means interme- 85
diate of the shut-off valves and said mem-
ber whereby movement of the latter out of
said parallel position will induce closure of
said valves.

2. In an apparatus of the class described,
having one or more generating cells pro-
vided with one or more water supply con-
duits having a shut-off valve, the generating 90
cell being provided with a cover at one end
thereof, means pivotally secured to the cell 95
and adapted to move across the cover, means
having operative relation with the first men-
tioned means and the cover and being ad-
justable in a lengthwise direction whereby
predetermined pressure will be exerted on 100
the cover when the first mentioned and sec-
ond mentioned means are brought into par-
allel position, and means intermediate of the
shut-off valve and the first mentioned means
whereby movement of the latter out of said 105
parallel position will affect the third men-
tioned means and induce closure of the
valve.

3. In combination with a generating cell
provided with one or more water supply 110
conduits, a valve in said conduit for con-
trolling the water supply for the cell, and a
cover for said cell, of means pivotally
secured to the cell and arranged to be moved
over the cover, a portion of said means being 115
adjustable and adapted to operatively en-
gage with said cover so that movement of
said means into a position substantially at
right angles to the cover will apply prede-
termined pressure thereto, and means in-
termediate of the first mentioned means and
said valve whereby the latter will move to 120
closed position when the first mentioned
means is moved out of the pressure apply-
ing position.

4. In combination with a generating cell
provided with a cover and a water supply
conduit, said conduit being provided with a
valve whereby passage through the conduit
may be controlled, of a member pivotally 125
secured to the cover and arranged to have
operative relation with the valve, said mem-
ber being adjustable lengthwise thereof so
that movement of the member and means into
parallel position will exert predetermined 130
pressure on the valve and maintain the lat-
ter in closed position.

- secured to the cell and arranged to move into a position substantially at right angles to said cover, extensible means intermediate of said member and the cover, arranged to apply predetermined pressure on the cover when said member and means are arranged substantially parallel, a portion of said member being arranged to project beyond the path of said member, and means intermediate of said portion and said valve and arranged to be affected by said portion so that when said member is moved out of said right angular position closure of the valve will be effected.
5. In combination with a receptacle provided with a cover and a fluid delivering conduit, a valve in said conduit for controlling the flow therethrough, of a yoke pivotally secured to said receptacle so as to swing through the arc of a circle, turn-buckle mechanism pivotally secured to said yoke and arranged to bear against the cover when the yoke and turn-buckle mechanism are brought into parallel position, said yoke being provided with a lug, and means intermediate of said valve and said lug, the relation of said means and lug being such that movement of the yoke out of parallel posi-
- 10
15
20
25

tion with the turn-buckle mechanism will induce closure of said valve and release pressure on said cover.

6. In combination with a receptacle provided with a fluid containing conduit having a valve, and a cover, of a yoke pivotally secured to said receptacle and arranged to move through the arc of a circle over said cover, extensible means arranged to exert pressure intermediate of the yoke and the cover when the yoke and said means are arranged parallel, and means intermediate of said valve and yoke adapted to be affected by said yoke when the latter is moved out of parallel position with the first mentioned means whereby closure of said valve will be effected.
